(57) **CLAIM**

The ornamental design for a headset, as shown and described.

DESCRIPTION

FIG. 1 is a front, top, and right side perspective view of a headset, showing our new design.

FIG. 2 is a front view thereof;

FIG. 3 is a right side view thereof;

FIG. 4 is a back view thereof;

FIG. 5 is a left side view thereof;

FIG. 6 is a top view thereof; and,

FIG. 7 is a bottom view thereof.

The dotted line portions of the drawings depict portions of the headset that form no part of the claimed design.

1 Claim, 4 Drawing Sheets(56)
